UNITED STATES PATENT OFFICE

168,824

WALL LIGHTING FIXTURE

David Borowitz, Chicago, Ill.

Application October 27, 1952, Serial No. 22,002

Term of patent 3½ years

(Cl. D48—4)

To all whom it may concern:

Be it known that I, David Borowitz, a citizen of the United States and a resident of Chicago, Illinois, have invented a new, original, and ornamental Design for a Wall Lighting Fixture, of which the following is a specification, reference being had to the accompanying drawing forming a part thereof.

The dominant features of my present design lie in the portions shown in full lines.

I claim:

The ornamental design for a wall lighting fixture, substantially as shown and described.

DAVID BOROWITZ.
